UNITED STATES PATENT OFFICE.

JAMES YOCOM, JR., OF PHILADELPHIA, PENNSYLVANIA.

DIVIDED CASTING.

SPECIFICATION forming part of Letters Patent No. 279,069, dated June 5, 1883.

Application filed May 1, 1883. (No model.)

To all whom it may concern:

Be it known that I, JAMES YOCOM, Jr., of the city and county of Philadelphia, in the State of Pennsylvania, have invented certain new and useful Improvements in Divided Castings, of which improvements the following is a specification.

My present invention is an improvement upon those for which Letters Patent of the United States Nos. 116,134 and 180,304 were granted and issued to me under dates of June 20, 1871, and July 25, 1876, respectively; and its object is to reduce the size and weight of the hinge-pieces employed, and to render the same properly adaptable to use in divided castings of different diameters, as well as to enable proper radial butting-faces to be formed upon the sections of the casting, irrespective of the greater or less diameter of the latter.

To these ends my improvements consist in the combination, with a divided casting formed in two sections, of a series of interlocking hinge-pieces, each having a hub or boss which is devoid of lateral facing pieces or extensions, and which is therefore adapted to project from the section in which it is embedded for equal distances on each side of its center, irrespective of the angle of its tongue with the face of said section; also, in the combination of a divided casting formed in two sections, a series of interlocking hinge-pieces, and a series of independent facing-pieces, which are, respectively, united to said sections in the operation of casting.

The improvements claimed are hereinafter more fully set forth.

In the accompanying drawings, Figure 1 is a transverse section through a pulley-hub embodying my invention at the line $x-x$ of Fig. 2; Fig. 2, a similar section through the same at the line $y-y$ of Fig. 1; Fig. 3, a view in perspective of one of the hinge-pieces; Fig. 4, a similar view of one of the facing-pieces; and Fig. 5 a view showing the relative arrangement of the hinge-pieces.

In the practice of my invention the divided casting, which may be a pulley-hub, collar, eccentric, coupling, or other structure which is to be fitted upon a shaft, is formed in two sections, A B, each having a semi-cylindrical recess suited to the diameter of the shaft. The

sections abut at the sides of said recess, and, as in my Letters Patent aforesaid, are connected by a series of interlocking hinge-pieces and a pair of pins or pivots. Each hinge-piece 55 is composed of a cylindrical hub or boss, a , and a curved tongue or arm, a' , projecting therefrom, said tongue being widened at and near its outer end to enable it to be firmly embedded in the casting. The hinge-pieces are inserted 60 and adjusted in the mold in which the sections A B are cast in such position that their tongues may extend as nearly as may be in arcs concentric with the recesses of the sections, and with the axes of their hubs in line with the 65 butting-faces of said sections, and are arranged to interlock, as shown in Fig. 5—that is to say, with the tongues of the hinge-pieces 1 of the section A in opposite direction to the tongues of the alternate hinge-pieces 2 of the section B. 70 That portion of the hub of each hinge-piece which projects above the face of the section in which it is to be embedded is clay-washed, to prevent the adhesion of the metal of the section thereto, and the metal poured into the 75 mold adheres, when cold, to the remaining portion of the hinge-pieces and retains them in position in the sections, which are connected by pins or pivots a'' passing through central perforations in the hubs of the hinge-pieces. 80

In my Letters Patent Nos. 116,134 and 180,304 aforesaid the hinge-pieces are shown as constructed with lateral wings or extensions, which form the butting-faces of the sections, and enable the same to be separated one from the 85 other after being cast. Such construction involves the objection of increasing the size and weight of the hinge-pieces, and, moreover, of limiting the normal use of a hinge-piece of given form to a casting of fixed diameter, for 90 the reason that such change in the inclination of the tongue as would be necessary to admit of the same being made substantially concentric with the recess of the section (as is desirable to afford proper strength) would effect a 95 corresponding inclination of the butting-face of the section from the radial plane with which it must correspond to make a true and proper joint. Under my present invention I form the hubs of the hinge-pieces without any lateral projections or facing-pieces whatever—that is to say, truly cylindrical on their exte- 100

rior for their entire or the major portion of their extent on each side of their tongues, or for such distance about the diameter at right angles to the center line of the tongue as will suffice to accommodate the greatest and the least diameters of castings in which the hinge-piece is designed to be employed. It therefore ensues that in any and all adjustments of the hub of the hinge-piece about the axis of its pin corresponding with the greater or less radius of the shaft-recess of the sections in which it is to be embedded there will be no protuberance or projection on the line of the butting-face of said section, which face may consequently be formed truly radial, as is desirable. The separation of said faces after the cooling of the casting may be effected either by setting in the mold a removable separating medium—as wire covered with asbestos—which is withdrawn after the cooling of the cast metal, or by the employment of independent metal facing-pieces a' , which are set in the mold in proper position to form the butting-faces of the sections A and B, and are clay-washed on their

sides which constitute said faces, being united 25 to the sections on their opposite sides in the operation of casting similarly to the hinge-pieces above described.

I claim as my invention and desire to secure by Letters Patent—

1. The combination, substantially as set forth, of a divided casting formed in two sections and a series of interlocking hinge-pieces united to said sections in the operation of casting the same, said hinge-piece being substantially cylindrical or devoid of lateral projections at and adjacent to the butting-faces of the sections. 30

2. The combination, substantially as set forth, of a divided casting formed in two sections, a series of interlocking hinge-pieces, and a series of independent facing-pieces, which are respectively united to said sections in the operation of casting. 35
